(57) **CLAIM**

The ornamental design for a hand mixer, as shown and described.

DESCRIPTION

FIG. 1 is a front perspective view of a hand mixer of the present invention.

FIG. 2 is a back perspective view of the hand mixer of the present invention.

FIG. 3 is an end elevation view of the hand mixer of the present invention.

FIG. 4 is an opposite end elevation view of the hand mixer of the present invention.

FIG. 5 front elevation view of the hand mixer of the present invention. The back elevation view of the hand mixer of the present invention is the mirror image of the front elevation view of FIG. 5.

FIG. 6 is a top plan view of the hand mixer of the present invention; and,

FIG. 7 is a bottom plan view of the hand mixer of the present invention.

In the drawings, the broken line showing the depending beater portion of the claim forms no part of the claim.

1 Claim, 5 Drawing Sheets
